RAIL FASTENING MEANS

Clovis Naud, Deschambault, Quebec, Canada

Application November 3, 1950, Serial No. 193,857

1 Claim. (Cl. 238—51)

1

The present invention relates to rail fastening means and more particularly to rail fastening means of provisory character adapted to be used for effecting temporary repairs on defective conventional sleepers or for reinforcing the rails in curves, on bridges and like locations.

According to present day practice in rail maintenance, the defective sleepers are either replaced by new one's, thereby involving a considerable amount of work, or else they are left in place until the general condition of the line warrants replacement of rail sections: this latter practice soon results in unsafe areas along the rail line which may cause accidents.

Accordingly, the general object of the invention is the provision of means to effect temporary repairs to a railway line without removing the conventional defective sleepers, said means being easily and quickly installed and being furthermore easily removable when a permanent repair is effected to the rails.

Another object of the invention is the provision of rail fastening means of the character described which may be used in a permanent manner to reinforce rail sections submitted to considerable side thrust as in curves, or rails located in dangerous areas such as bridges, mountain sides and the like.

Yet another object of the present invention is the provision of rail fastening means in the form of a tie plate provided with rail guiding means for automatically positioning said rails at the correct gauge or spacing, said guiding means serving furthermore to clamp said rails in a very secure position.

Another very important object, according to the present invention, is the provision of a transverse base member of a length substantially greater than the spacing normally separating a pair of rails, said base member adapted to be positioned under said rails so as to project from under their outer sides, and provided with integral upstanding eyes for insertion of wedge shaped members adapted to engage and bear against the foot of the rails whereby providing fastening means adapted to withstand considerable side thrust exerted against said rails.

Another important object, according to the present invention, is the provision of a base member of the character described which is in the form of a beam adapted to be positioned between the sleepers in order to further reinforce rails laid according to conventional practice as on bridges, curves and other locations.

Still another important object, according to the

2

present invention, is the provision of a base member of the character described in the form of a base plate adapted to be positioned under a pair of spaced rails and secured to the upper face of a conventional sleeper.

Still another important object, according to the present invention, is the provision of a base plate of the character described hereabove adapted to be secured to a sleeper by means of conventional spikes, said base plate formed as to enable quick and easy removal of said spikes when using a conventional tool such as a crowbar.

Yet another important object, according to the present invention, is the provision of a base plate in combination with wedge members adapted to engage eyes formed on said base plate and to bear against the foot of the rails on both sides thereof, said wedge members being further provided with suitable recesses for easy removal of the same.

The foregoing and other important objects according to the present invention will become more apparent during the following disclosure and by referring to the drawings in which:

Figure 1 is a perspective view of a pair of spaced rails secured to two embodiments of a base member according to the present invention;

Figure 2 is a perspective fractional view of a rail secured to a base plate according to the present invention;

Figure 3 is a section taken across the upstanding eye of the base plate according to the invention;

Figure 4 is a section along line 4—4 of Figure 3;

Figure 5 is a fractional perspective view of the second embodiment according to the invention, showing the rails about to be positioned in place;

Figure 6 is a longitudinal section along the base beam of the present invention showing how the rail is fastened in position;

Figure 7 is a section similar to that of Figure 6 showing how the wedge members are removed; and

Figure 8 is a section along line 8—8 of Figure 7.

Referring now more particularly to the drawings in which like references indicate like elements throughout, the letter A denotes a pair of rails spaced according to standard gauge and having a foot or base flange denoted by the letter B.

According to one embodiment of the present invention, the base member consists in a base plate 1 of preferably rectangular shape and of a length substantially greater than the spacing

between the rails A so as to project from under the outer side thereof when laid beneath and transversely of said rails as shown in Figure 1.

The base plate 1 is adapted to be positioned under the rails A and on top of a conventional sleeper of wood or other conventional material and indicated by the letter C.

The upper face of the base plate 1 is provided with a plurality of suitably positioned raised portions 2 through each of which extends a hole for insertion of a standard spike D in such a manner that its head will bear against said raised portion 2 but will project therefrom to extend in spaced relationship with the upper face of the base plate 1 when in position so as to be easily removed with the help of a crow bar or the like.

According to the present invention, two pairs of upstanding eyes 3 are integrally formed at the upper face of the base plate 1 and aligned longitudinally of said base plate. In each pair of eyes 3, the spacing therebetween is only slightly larger than the width of the foot B of the standard rail A to practically eliminate any sideways displacement of said rail when inserted between said pair of eyes 3. Thus the latter serve as guiding means for positioning the rails.

Furthermore, the spacing between each pair of eyes at both ends of the base plate 1 is such that the correct gauge for the rails A will be obtained when the latter are inserted in place. In this manner, when laying tracks with the base plate, according to the invention, it is not necessary to check or measure the spacing between the rails because such spacing is obtained automatically when the rails are inserted between the eyes 3.

Wedge shaped members 4 are adapted to be inserted through the eyes 3 for bearing against the upper side of the foot B of the rails A on both sides of said rails thereby resulting in a very secure fastening for said rails. The wedge members 4 are preferably hammered into position as shown in Figure 6. But they may be easily removed because they are provided adjacent the other bigger end and on the top portion thereof with a recess 5 for insertion of a suitable tool such as shown as E in Figure 7.

The wedge members 4 have preferably a flat lower face 6 as shown in Figure 4 and a somewhat rounded top face 7 corresponding to the shape of the top portion of the eye 3.

Although the combination of the wedge members 4 and of the eyes 3 insure a very efficient gripping of the rails A, the latter may be further fastened on the inside by means of standard spikes such as shown at 8 in Figure 1. Obviously, suitable holes are made in the base plate 1 to receive said spikes 8.

The base member, according to the invention, may take the form, instead of the base plate 1, of a beam having a rectangular or other suitable cross-section for use as a temporary or supplementary sleeper adapted to be laid between conventional sleepers C. Such base member in the form of a rectangular beam is shown at 9 in Figure 1 and is illustrated more particularly in Figures 5 to 8.

The beam 9 is provided with two pairs of U-shaped straps 10 secured in an inverted manner to both sides of the beam 9 as by welding. The bridge portion of these U-shaped straps 10 is spaced from the top face of the beam 9 so as to

provide an eye substantially similar to the eyes 3 of the previous embodiment for insertion of similar wedge members 4.

Obviously the spacing between the straps 10 is the same as the spacing defined above for the eyes 3 on the base plate 1 so as to provide guiding means and fastening means at the same time for the rails A.

The beam 9 could be used as supplementary fastening means for locations subjected to extra heavy stresses such as curves or as a further security in dangerous locations such as bridges and the like.

The beams 9 are easily put in position without having to displace the conventional sleepers C.

Rails equipped with the base plate 1, according to the present invention, will present a high degree of safety because even when the conventional sleepers C are in bad condition the base plate 1 will nevertheless be used to hold the rails firmly in place because of its high leverage action. This is not possible with standard tie plates, the gripping action of which depends solely on the gripping power of the spikes inserted into the wooden sleepers C. Therefore, when the latter become rotten, the spikes loosen up and the rails rapidly become a cause of accidents.

It will be noted that when rails are provided with a base plate 1, according to the invention, the conventional sleeper C may be removed and replaced without having to untie said base plate from the rails: it is only necessary to withdraw the spikes 3 and 8.

While preferred embodiments according to the present invention have been illustrated and described, it is understood that various modifications may be resorted to without departing from the spirit and scope of the appended claim.

What I claim is:

Fastening means for a pair of spaced rails comprising a base member in the form of a solid beam adapted to be positioned transversely under said rails between sleepers, said beam of a length greater than the spacing of said rails, at least two pairs of upstanding eyes in the form of inverted U-shaped straps each having one of its legs secured to the opposite sides of said beam, and each having its bridge portion spaced from the upper face of said beam, the said straps of each pair spaced to receive and position therebetween the foot of said rails, the spacing between each pair of said straps corresponding to the spacing of said rails, and wedge members engaging said straps and bearing against the foot of said rails.

CLOVIS NAUD.
